HANDLE FASTENING DEVICE

Frank M. Spezzano, Bristol, Pa.

Application August 22, 1933, Serial No. 686,194

1 Claim. (Cl. 306—33)

This invention relates to handle fastening devices, and has for an object to provide improved means for fastening a handle of wood or like material into the eye of an implement of rigid material.

A further object of the invention is to provide a wedge for expanding the inserted end of a handle, and with a second wedge employed as a locking means for the first expanding wedge.

10 A further object of the invention is to provide a wedge having means for accommodating a second wedge, which said second wedge is slotted, and means provided by the first mentioned wedge for diverging the ends of the second wedge into locking position.

The invention, therefore, comprises a wedge which is to be driven into the handle and provided with a longitudinal slot having an inner wedge, with a second wedge slotted longitudinally driven into the slot of the first mentioned wedge and by engagement with the inner expanding wedge, diverged into locking engagement with the handle material.

The drawing illustrates an embodiment of the 25 invention and the views therein are as follows:

Figure 1 is a view of the invention in side elevation shown applied to a conventional type of hammer.

Figure 2 is an end elevation of the handle inserted into a hammer head with the invention applied thereto.

Figure 3 is a sectional view taken on line 3—3 of Figure 2.

Figure 4 is a perspective view of the first or 35 larger wedge,

Figure 5 is a perspective view of the smaller or secondary wedge, and

Figure 6 is a view in end elevation of the larger wedge, as indicated by arrow 6 at Figure 4.

40 Like characters of reference indicate corresponding parts throughout the several views.

The present invention is adapted to be associated with a great variety of handles applied to a great variety of implements. Ordinarily, 45 such handles are constructed of wood and some expansion of the handle is required to efficiently lock the handle into the eye of the implement. In the drawing, a hammer head 10 has been shown which, however, is to be understood as 50 merely illustrative as any other type of implement, is fully within the scope of the present invention.

The implement of whatever type is provided with an eye, indicated at 11, into which the handle 12 is inserted in the usual well known manner.

55 After such insertion the wedge A is driven into the handle. The width of this wedge A will correspond approximately, or as nearly approxi-

mately, as found desirable to the longest dimension of the eye and is of sufficient length to extend a considerable distance within the eye. The elongated wedge itself is slotted longitudinally at 13 throughout the major part of its length and terminates in a wedge-shaped connecting bar 14 which constitutes an expander, the purpose of which will appear hereinafter. The inserted end of the wedge is, of course, tapered, as at 15, as is usual in the case of such wedges. The secondary wedge B is slotted at 16 and is of such thickness as to substantially fill the slot 13 laterally. It is driven in to form with the wedge A a cross, as indicated at Figure 2.

The slot 16 extends the major part of the 15 length of the member B and the adjacent edges of the slot are parallel except at the normally inner end, where they are tapered reversely, as shown at 17. The wedge B is longer than the wedge A so that the tapers 17 come in contact 20 with the wedge bar 14 and diverged by continued driving so that the positions 18, as shown at Figure 3, are attained. As these ends expand as shown, they are driven into the material of the handle 12 and thereby the wedge B is locked 25 firmly against withdrawal from the handle 12 and the wedge B thus effectively locks the wedge A in position. It should be noted that while the slot 16 extends the major portion of the length 30 of the wedge B, it terminates a sufficient distance from the outer end to maintain the said outer end from bending.

It will, therefore, be seen that the material of the handle is not only expanded by the wedge A, but is also expanded by the wedge B and that, 35 by reason of such expansion, the handle is locked firmly in the eye of the implement.

Of course, the handle fastening device herein described may be modified and changed in various ways without departing from the invention 40 herein set forth and hereinafter described.

I claim:—

A handle fastening device comprising an elongated wedge having a longitudinal slot extending the major portion of its length and terminating in an expander, a second wedge adapted to be inserted into the slot of the first mentioned wedge and intersecting the same, said second mentioned wedge being of greater length than the first said wedge and provided with a longitudinally disposed slot of less width than the thickness of the first said wedge, the walls of the slot being parallel except at the extremities where they are reversely tapered and adapted to be expanded by driving contact with the expander of the first mentioned wedge to oppositely directed curvatures within the body of the handle.

FRANK M. SPEZZANO.
